JOIST-SUSPENDED FURNACE STRUCTURE

Thomas C. Gleason, Detroit, Mich., assignor to
 Chrysler Corporation, Highland Park, Mich.,
 a corporation of Delaware

Application October 10, 1950, Serial No. 189,421

2 Claims. (Cl. 126—99)

1

My invention relates to a furnace structure.

More particularly, my invention relates to an improved compact air heating furnace structure which may be resiliently mounted on the building in which it is placed.

The present invention deals with an improvement on an air heating furnace structure disclosed in the copending application of Gleason et al., Serial No. 171,452, filed June 30, 1950. In the past, furnaces for buildings have generally been shipped in parts and assembled at the location where the installation is made. The furnace structure disclosed herein may be factory assembled, moved into the building as a unit and thereafter conveniently resiliently mounted on the building.

The principal object of my invention is to provide a furnace of the type disclosed in the aforementioned copending application with improved structure for resiliently mounting the furnace within a building.

Another object of my invention is to provide an improved resilient mounting which may be conveniently utilized to mount an elongated furnace between the joists in the floor of a building.

Other objects and advantages of my invention will become more apparent from the following description taken in connection with the accompanying drawings in which:

Fig. 1 is a perspective view of a furnace illustrating the application of my invention thereto.

Fig. 2 is a plan view of the furnace showing the general arrangement of parts therein.

Fig. 3 is a side elevational view of the structure shown in Figs. 1 and 2.

Fig. 4 is a sectional view taken on the line 4—4 of Fig. 3.

Fig. 5 is a perspective view of the bracket assembly shown in Figs. 1 to 4.

Fig. 6 is a sectional view similar to Fig. 3 showing a modification of my invention.

Referring to the drawings, I have shown a furnace, generally designated by the numeral 10, which is mounted between spaced longitudinally extending joists, one of which is shown at 12. The mounting structures, generally designated by the numeral 14, are disposed at four different locations and are adapted to support the furnace 10 relative to the joists. Since all mounting structures 14 are identical, as shown in Figs. 1 to 5, a description of one will suffice for all.

Referring now more particularly to Figs. 4 and 5, the mounting structure 14 comprises a gen-

2

erally U-shaped bracket 16 having outwardly extending flanges 18 which are welded to U-shaped securing members 20. The members 20 are provided with openings 22 and 24 which receive nails 26 and 28, respectively, the latter serving to securely attach the members 20 to the joist 12. The U-shaped bracket 16 is provided with a bite portion 30 having a threaded centrally located opening 32 which receives a bolt 34 therein. The bolt 34 is provided with a head portion 36 which is bonded to the lower surface of a cylindrical yieldable rubber-like cushion member 38. The upper surface of the member 38 is bonded to the head portion 40 of the bolt 34, the latter extending through an opening 44 in a small leg 46 of an L-shaped bracket 48. The leg 46 is disposed over the yieldable member 38 between the legs of the U-shaped bracket 16 and is provided with a long leg 50 which extends vertically downwardly from the bracket 16 and is provided with an opening 52 at the lower end thereof. The opening 52 receives a bolt 54 which extends through an opening 56 in the furnace 10 and is threaded into an anchoring member 58 which is securely fixed to the floor of the casing of the furnace. The opening 56 is provided with a rubber grommet 60 which lines the opening, cushions the leg 50 of the L-shaped bracket 48 against the furnace as well as prevents the influx of any dirt within the casing of the furnace. The bolt 42 is provided with a nut 62 which secures the short leg 46 to the head portion 40 of the bolt 34. The bolt 34 is provided with a lock nut 64 which not only may be tightened down on the underside of the bite portion 30 of the bracket 16 to lock the bolt in place but also serves to fasten a cover member 66 in place. The cover member 66 is provided with a lower horizontal portion 68 which has an opening 70 through which the bolt 34 extends.

In Fig. 6 I have shown a modification of my invention wherein a U-shaped bracket 72 having legs 74 and 76 is secured to the joist 12 by nails 78 and 80, respectively. The U-shaped bracket 72 is provided with a bite portion 82 which is inclined clockwise approximately 20° as shown in Fig. 6. This bite portion is provided with an opening 84 which receives a rod 86 extending therethrough, one end of the rod being provided with an opening 88 which receives a bolt 90 extending from the furnace 10. A nut 92 secures this end to the furnace. The other end of the rod 86 receives a cylindrical yieldable rubber-like member 94 which is pro-

vided with a centrally located opening 96 and is disposed around the rod at a location between the legs 74 and 76 of the U-shaped bracket 72. The extreme end of the rod 86 disposed within the bracket 72 is provided with a circular disc 98 and nut 100 which serve to hold the assembly together, the weight of the furnace 10 being supplied through the rod 86 and disc 98 to the yieldable member 94 and hence to the bracket 32 and joist 12.

In Figs. 1, 2 and 3, I have shown the furnace 10 provided with oppositely disposed openings 102 and 104. The opening 102 allows the heated air to pass from the furnace while the opening 104 receives the cold air returning to the furnace. The opening 102 is provided with a flexible coupling 106 which connects the opening to ducts 108 while the opening 104 is connected by a flexible coupling 110 to duct 112. The flexible couplings 106 and 110 are preferably made of fabric material such as canvas or similar material and are accordion pleated to facilitate installation as well as flexibility. For the purpose of illustration, the duct 108 is connected to duct 114 and hot air register 116 disposed in the wall 118 while the duct 112 is connected to duct 120 and cold air return register 122 disposed in the wall 124.

It will be seen from the drawings that the furnace 10 is completely resiliently mounted relative to the joists, one of which is shown at 12. The resilient mounting is supplied by the mounting structures 14 as well as the flexible connectors 106 and 110. By this construction the vibrations caused by the movable parts disposed within the furnace 10 will not be transferred to the joists. It will also be noted that by my improved construction of the furnace 10, the furnace may be conveniently placed between the joists and allow sufficient head room for a normal size person to walk beneath the furnace. Similarly, this construction adds more usable space to the room in which it is located since it is not mounted on the floor of the room as most furnaces are but it is rather mounted in the ceiling of the room.

While I have illustrated and described but two embodiments of my invention, it is to be understood that such is for the purpose of illustration only, and it is contemplated that those skilled in the art may modify certain details without de-

paring from the spirit or scope of the invention as defined in the claims appended hereto.

I claim:

1. In combination with spaced floor joists of a building structure, a sheet metal enclosed air heating furnace of a generally elongated construction having a portion disposed between said joists and having anchor means disposed within the sheet metal enclosure adjacent an opening therein, and mounting means having a first portion secured to one of said joists and a second portion extending through the opening in said sheet metal and being secured to said anchor means, said mounting means including first yieldable means disposed between said first and second portions for yieldably supporting said furnace relative to said joists and second yieldable means lining said opening and engaging said second portion of said mounting means.

2. In a building structure including spaced floor joists and a generally elongated air heating furnace unit disposed in part between said joists; a mounting device adapted to resiliently support said furnace unit relative to said joists comprising a U-shaped bracket including leg portions adapted to be secured to a joist and a bight portion having an opening therethrough, a substantially L-shaped bracket having one end adapted to be secured to said furnace unit and its other end disposed over said bight portion and between said leg portions, and resilient means including a rubber-like member and oppositely disposed end pieces bonded to said member, one of said end pieces extending through the opening in and being adjustably secured to the bight portion of said U-shaped bracket and the other end piece being secured to said other end of said L-shaped bracket.

THOMAS C. GLEASON.
